UNITED STATES PATENT OFFICE.

BENNIE P. HANSON AND NELS I. NELSON, OF BANCROFT, IOWA.

LOADING-MACHINE.

1,229,262.

Specification of Letters Patent. Patented June 12, 1917.

Application filed October 19, 1915, Serial No. 56,696. Renewed November 11, 1916. Serial No. 130,922.

To all whom it may concern:

Be it known that we, BENNIE P. HANSON and NELS I. NELSON, citizens of the United States, residing at Bancroft, in the county 5 of Kossuth and State of Iowa, have invented certain new and useful Improvements in Loading-Machines; and we do hereby declare the following to be a full, clear, and exact description of the invention, such as 10 will enable others skilled in the art to which it appertains to make and use the same.

This invention relates to loading machines and more particularly to a machine for handling and loading manure.

15 One of the objects of this invention is to provide a device whereby the manure can be easily and quickly gathered from the barn-yard or other place and effectively placed in a pile or in a pen, or loaded into a wagon, 20 manure spreader, or other transporting vehicle.

Another object of this invention is to provide a device whereby the gathering means can be locked in raised position in a convenient and certain manner.

Another object of this invention is to provide a ready attachable and detachable connection between the gathering means and the flexible lifting means therefor.

30 Another object of this invention is to provide the device with means whereby the same may be readily moved from place to place.

Another object of this invention is to 35 provide a resilient support for the lifting means whereby to obviate sudden jerks which might be occasioned by the gathering means encountering obstructions.

Another object of this invention is to 40 provide a device so constructed that the same may be used in conjunction with a transporting vehicle for loading the latter, or that certain parts of the device may be detached from the remainder and mounted 45 upon the body of the vehicle when desired.

Other objects and advantages of this invention will be hereinafter more clearly set forth in the specification and pointed out in the claims.

Similar characters of reference refer to 50 similar parts throughout the specification and drawings, in which,

Figure 1 is a perspective view of the device complete for operation.

Fig. 2 is a side view of the gathering 55 means and the elevating means therefor.

Fig. 3 is a detail view of the elevating means.

Fig. 4 is a further detail view showing the lifting means locked in elevated position in 60 the support therefor.

Fig. 5 is an end view showing the manner of mounting the tackle block upon the supporting frame therefor.

Fig. 6 is an end view of the lifting pulley 65 and block.

Fig. 7 is a perspective view showing the manner of mounting certain parts of the device upon a wagon or other transporting vehicle.

70 Fig. 8 is a perspective view of a modified form of the gathering means.

Fig. 9 is a side view of another modified form of the gathering means.

In Fig. 1 of the drawings, the base frame 75 of the device may be constructed of any suitable material, but is preferably formed of angle iron or steel where feasible. The frame consists of the sills A and B, and upon the sills, adjacent their forward ends, is secured the platform C, preferably formed of wooden boards. Secured upon the sills A and B, rearwardly of the platform C, is the cross bar D, braced to the sills A and B by the rods E. The ends of the cross bar D 80 project outwardly beyond the sills A and B, and upon these ends are secured the brackets F, formed with the pivot pins or trunnions G, provided with the cotter pins H, though other securing means may be employed. 85 Upon the sills A and B, in proximity to the cross bar D, are the supports I and J, braced at their forward sides to the sills A and B by the rods K, and braced at their inner sides to the cross bar D by the rods L. The supports I and J are braced at their rear 90 sides to the rear ends of the sills A and B by the bars M. The lower ends of the bars

M are provided with the upturned forks N, in which are pivotally mounted the transporting wheels O.

Pivotaly mounted upon the trunnions G 5 of the cross bar D of the base frame, is a suitable frame 2, in this instance preferably formed of piping, provided at its lower ends with the pivot ears 3 for embracing the trunnions G. Suitable springs 4 and 5 are 10 provided and have one of their ends secured to the upper ends of the standards I and J, and their other ends secured to the side portions 6 and 7 of the frame 2 to resiliently retain said frame in elevated position upon the base frame as shown.

At the center of the top portion of the frame 2 is fastened a tackle block or housing, comprising the side members 9 and 10 having the outstanding flanges 11 and 12 20 respectively to suitably fasten the tackle block to the frame 2 by means of bolts 13 or other fastening means. An upper pulley 14 is mounted between the plates 9 and 10 by means of a suitable shaft 15, and a lower pulley 16 is likewise mounted between the plates 9 and 10 by means of the shaft 17, the last mentioned pulley being slightly in front as well as below the first mentioned pulley 14. One end of a suitable cable 18 is secured 25 around the pulley 14, and is then passed around the lifting pulley 19, to be herein-after described in detail, and over the pulley 16, thence over the fore part of the device to be attached to a suitable source of power, 30 preferably that of a horse. The last mentioned part of the cable 18 may be passed over and beyond the fore part of the wagon that is being loaded, the wagon being backed upon the platform C, so that the hind wheels 35 of the wagon rest upon the platform C and thus maintain the stability of the device during the loading operation. The platform C is primarily designed for this purpose, though the platform may be otherwise 40 weighted, or the base frame otherwise secured, to prevent casual displacement of the device if desired.

The lifting pulley 19 is mounted between two plates 22, which are suitably fastened 45 together by means of the pulley shaft 23 and the pins 24 and 25. The ends of the pin 25 extend beyond the outer sides of the plates 22 and are adapted to be seated in the elongated apertures 26 formed within 50 the plates 9 and 10 of the tackle block, previously mentioned, for efficiently locking the lifting device in elevated position within the pulley block, as plainly shown in Fig. 4.

A suitable gathering fork or rake is provided, the preferred form being shown in 55 Fig. 2, and consists of a plurality of tooth bars 27, suitably fastened to a cross beam 28 by means of the U-bolts 29 which are locked around the tooth bars 27 and through

the cross beam 28 by means of suitable nuts 60 30 or other suitable form of fastening means, certain of said means likewise supporting the ends 31 of the handles 32. The upper end portions of said tooth bars are suitably supported in a second cross beam 33 and 70 locked thereagainst by the U-bolts 34 of the form previously described, said U-bolts being locked by the nuts 35 after the brace bars 36 are mounted over the ends of certain of said U-bolts 34, the opposite ends of 75 said brace bars 36 being fastened as at 37 to the handles 32 to brace the same. A third cross beam 38 is mounted between the cross beams 28 and 33 adjacent the bend of the tooth bars 27 and fastened by means of 80 the U-bolts 39 in a manner as previously described.

The center tooth bar is elongated as at 40 and looped as at 41 to provide a track arrangement of an even contour through- 85 out, in which travels a connection 42, said connection having mounted in one end thereof, by means of a suitable shaft 43, a pulley 44 adapted to travel along the under side of the loop 41. The upper end of the connection 42 is forked as at 45 and 46, between which forks is pivotally mounted a hook 47, said hook being mounted by means of the pivot pin or bolt 48, and is adapted to be 90 removably hooked over the pin 24 previously 95 described.

In Fig. 7 is shown the manner of mounting a portion of the loading device, shown in Fig. 1, upon a wagon, manure spreader, or other transporting vehicle when desired. 100 This is accomplished by detaching the ears 3 of the frame 2 from the trunnions G of the base frame, and also the springs 4 and 5 from the standards I and J, and securing the ears 3 upon the trunnions of the brackets 3' secured upon the outer sides of the body 1 of the vehicle, and the springs 4 and 5 to the apertured brackets 4' and 5' secured upon the top edge of the body of the vehicle. That portion of the cable 18, which 110 passes over and beyond the forward end of the vehicle, may be passed through idle pulleys arranged upon the front end of the vehicle, as shown at 20 and 21 if desired.

In the modified form of the fork or rake 115 shown in Fig. 8, the two cross beams 49 and 50 are used instead of the three beams as shown in Fig. 2, the handles 32 being fastened to the cross beam 49 and the brace rods 36 to the cross beam 50 in a manner 120 described in the preferred form of the invention. The tooth bars of this construction are curved as at 51 in a semi-circular form rather than having a straight portion 52, as illustrated in Fig. 2 in the preferred 125 form of the fork or rake.

The further modified form of the fork or rake shown in Fig. 9 is essentially simi-

lar to that shown in Fig. 8, excepting the loop 41 is provided with the upset portion 53 to provide a recess into which the pulley 44 may drop when the fork is drawn beneath the tackle block of the frame 2, to efficiently balance the fork with its load while the same is being raised from the ground and carried over the load.

In operation, the fork or rake is drawn rearwardly at any desired angle, as far as is necessary with the pulley 44 of the connection at the forward end of the loop 41, whereupon the horse or the power at the forward end of the cable is started up, and the rake is gradually drawn toward the supporting frame 2 and its tackle block, gathering the manure as it travels in this direction. This operation will continue until the fork or rake is drawn beneath the supporting frame 2 and the tackle block, at which point the cable begins to draw the fork and its load upwardly, and at this instance the pulley 44 will travel along the under side of the loop 41 of the fork toward the center of the loop, in the structures shown in Figs. 2 and 7, or drop into the recess 53 of the structure shown in Fig. 8, whereby the rake and its load will be evenly balanced as it travels upwardly. Prior to the fork reaching its uppermost position, the projecting ends of the pin 25 will engage the sloping edges of the plates 9 and 10 of the tackle block and be directed and seated into the slots 26 of the plates 9 and 10, whereupon the fork and its connections will be locked in elevated position. The continued drawing of the cable will now cause the frame 2 and the fork and its load to be swung forwardly, the frame 2 assuming the same angular position in its forward position as it initially assumed in its rearward position. The forward position of the frame 2 now places the loaded fork over the pile, pen, or the vehicle to be loaded, whereupon by a slight tilting of the fork its load will be discharged with little or no exertion upon the operator. After the load has been dumped from the fork, the cable is then slackened and the fork and the frame 2 is drawn rearwardly until the frame 2 assumes its rearmost position, whereupon a slight additional pull upon the fork will cause the locking ends of the pin 25 to become dislodged from the apertures 26 of the tackle block and the fork thereby lowered to the ground, whereupon the fork is again drawn rearwardly and the operation repeated as before described.

While the operation of the device has been described as a machine for loading manure, it is to be understood that this device is equally adaptable for loading sand, gravel, dirt and the like, the only changes being nec-

essary for this latter use would be in the 65 teeth of the fork, and in this latter instance it would only be necessary to cover the lower portions of the teeth with a covering of sheet iron or other thin metal.

Having described our invention, what we 70 claim as new and desire to secure by Letters-Patent, is:—

1. A loading device, comprising a base member, a supporting frame pivotally mounted upon said base member, a housing 75 rigidly mounted upon said frame and having a plurality of pulleys therein, a cable riding over said pulleys and carrying a lifting device, a rake having a looped portion thereon, means riding in said looped portion 80 and connected to said lifting device, and means carried by said lifting device adapted to lock in said housing when said lifting device is in elevated position.

2. A loading device, comprising a rake, 85 consisting of a number of tooth bars, a plurality of cross beams assembling said tooth bars, handles attached to one of said cross beams, bracing members connected at one end to another of said cross beams, and at 90 their opposite ends to said handles to brace the same, looped means upon said rake, connecting means riding in said looped means, and a lifting device connected to said connecting means to lift said rake. 95

3. A loading device, comprising a pivoted support having a rigidly mounted housing thereon containing pulleys, said housing having apertures therethrough, a cable riding over said pulleys and carrying a lifting 100 device, said lifting device having an extended pin adapted to be seated in said apertures to lock said lifting device in elevated position, a rake having a looped portion, and a flexibly mounted connecting 105 means riding in said looped portion removably connected to said lifting device to raise said rake upon the operation of said lifting device.

4. A loading device, comprising supporting means, lifting means, locking means carried by said lifting means for locking said lifting means to said support when in elevated position, a rake having an elongated looped portion, and flexible means riding in 115 said looped portion removably hooked to said lifting means adapted to raise said rake upon the operation of said lifting means.

5. A loading device, comprising a base member provided with transporting wheels, 120 a supporting frame upon said base member, means for pivotally mounting said supporting frame upon said base member, means for resiliently supporting said supporting frame upon said base member, a housing 125 upon said supporting frame provided with apertures, pulleys within said housing, a cable for traveling over one of said pulleys, a

lifting device carried by said cable, a rake having a loop, means for traveling in said loop and connected to said lifting device, and means carried by said lifting device adapted to lock in the apertures of said housing when said lifting device is in elevated position.

In testimony whereof we have signed our

names to this specification in the presence of two subscribing witnesses.
